UNITED STATES PATENT OFFICE

153,231

DESIGN FOR A BOTTLE

Frank C. Nahser, Chicago, Ill.

Application October 4, 1945, Serial No. 123,040

Term of patent 3½ years

(Cl. D58—8)

To all whom it may concern:

Be it known that I, Frank C. Nahser, a citizen of the United States of America, residing at Chicago, Cook County, Illinois, have invented a new, original, and ornamental Design for a Bottle, of which the following is a specification, reference being had to the accompanying drawings, forming a part thereof.

Referring to the drawings, Fig. 1 is a top plan view of a bottle showing my new design; Fig. 2 is a perspective view, and Fig. 3 is a bottom plan view of the same.

I claim:

The ornamental design for a bottle, substantially as shown.

FRANK C. NAHSER.
